UNITED STATES PATENT OFFICE

BYERS W. KADEL, OF BALTIMORE, MARYLAND, ASSIGNOR TO THE SYMINGTON COMPANY, OF NEW YORK, N. Y., A CORPORATION OF MARYLAND

CAR TRUCK

Application filed April 6, 1926, Serial No. 100,140. Renewed July 31, 1929.

This invention relates to railway car trucks and, more particularly, to the construction of the side frames and the associated spring plank, bolster and spring plates and the arrangement of a six unit nest of springs cooperating therewith whereby increased truck capacity may be secured.

The principal object of my invention, generally considered, is the improvement in design of the side frames, bolster, spring plank and spring plates whereby a greater number of springs than normally employed may be utilized without radically changing the construction of the parts.

An object of my invention is the employment of a six group nest of springs hexagonally arranged in place of the standard five group nest of springs, for supporting the bolster on the truck side frames whereby increased truck capacity is secured, the side frames, bolster, spring plank and spring plates being modified for efficiently accomplishing the desired result.

Another object of my invention is the design of side frames, bolster, spring plank and associated spring plates for permitting the employment of an additional spring unit with each side frame, said spring unit together with the standard five units being arranged in the form of an equilateral hexagon with a long axis disposed transversely of the side frame with which employed thereby making it possible to employ a spring plank therewith of standard end width, the spring plank seat portions of the side frames being so constructed and reinforced by webs or brackets that an adequate area of sufficient strength is provided for properly supporting the spring plank and its associated springs, spring plates and bolster.

A further object of my invention is the increase in capacity of railway car trucks normally employing a standard five unit nest of springs, for supporting each end of the bolster with respect to the associated side frame, by using an additional spring unit and arranging the six spring units in hexagonal form, the four outer springs of the standard five unit nest of springs being kept in normal position and the other two springs

positioned, respectively, inwardly and outwardly of the position of the central spring unit of the standard nest of springs, the whole nest being positioned on an associated spring plank so that it balances about the longitudinal center line of the side frame, the spring plank being preferably of standard width at its ends but correspondingly lengthened because of the increased width of the spring group, the bolster being of standard construction except that the portion thereof engaging the supporting spring assembly is locally extended to receive the innermost spring of the group, the total length of said bolster, however, corresponding with the increase in width of the spring group.

A still further object of my invention is the provision of a six group nest of springs for supporting each end of a truck bolster whereby the capacity of the truck with which employed is increased, said springs replacing the A. R. A. standard five group nest of springs and being positioned with respect to the side frames so that the center of gravity of each spring group lies on the longitudinal center line of the corresponding frame, the six groups of the nest of springs being preferably arranged as a regular hexagon with a long axis arranged transversely of the frame, the associated spring plates being correspondingly formed and provided with centrally disposed cupped portions adapted for receiving retaining means of shorter length than normal thereby obviating the necessity for forming apertures for said retaining means in the associated spring plank and frame, said spring plates also being formed with locating bosses arranged on the longitudinal center line of gravity of the plates, said bosses being adapted for reception in positioning apertures of standard location in the associated spring plank, said spring plank being of standard width at its ends but correspondingly lengthened and formed with bosses at its ends for limiting outward movement of the nest of springs.

Other objects and advantages of the invention relating to the particular arrangement and construction of the various parts will become apparent as the description proceeds.

Referring to the drawings illustrating my invention, the scope whereof is defined by the appended claims:

Figure 1 is a fragmentary side elevation 5 of a truck, shown partly in section on the line 1—1 of Figure 3 and particularly showing the construction of the various members associated with the bolster springs.

Figure 2 is a horizontal sectional view of a 10 fragmentary portion of the truck on the line 2—2 of Figure 1 looking in the direction of the arrows.

Figure 3 is a transverse sectional view on the line 3—3 of Figure 1 looking in the direction of the arrows.

Figure 4 is a plan of the spring plank seat portion of the truck side frame, the position of the springs thereover being indicated diagrammatically by dot and dash lines.

Figure 5 is a top plan of the bottom spring plate and is likewise a bottom plan of the top spring plate.

Referring to the drawings, in detail, like parts being designated by like reference characters, a truck side frame 1 is shown fragmentarily and said frame, in the present embodiment, is of integral cast construction embodying a compression member 2, a tension member 3, and bolster guide columns or struts 4 spacing intermediate portions of said compression and tension members, leaving a window opening therebetween. The compression member 2, over the bolster opening, is shown as substantially channel or inverted U shape in cross section, the bolster guide columns are shown of similar construction at the bolster guiding portions thereof, while the tension member 3, beneath the bolster opening 5, is preferably of box shape in cross section and formed with an upper web 6, a lower web 7, a front or outer web 8 and a rear or inner web 9, said webs 8 and 9 being preferably upright or vertical and extending from the side edges of the web 7 to the web 6. In order to form a spring plank seat portion of ample width, the web 6 is extended laterally beyond the upper ends of the web 8 and 9 forming outward or front flange or shelf portions 10 and inward or rear flange 50 or shelf portions 11.

In the embodiment illustrated, the spring plank 12 rests directly on the upper web 6 of the tension member which forms the seating portion therefor. Although only one side frame is shown, it is obvious that the truck comprises two frames and each end of the spring plank is supported on one frame, as is usual. The upper surface of said spring plank seat portion is preferably formed with A. R. A. standard squaring lugs 13 which engage in corresponding apertures 14 in the spring plank for maintaining the desired relation between the spring plank and side frame. The end of the spring plank 12 may 65 be of standard width, if desired, but is longer

than normal and of slightly different construction for reasons to be pointed out hereinafter. As shown most clearly in Figures 1 and 2, the spring plank is of channel or U construction and the lower web thereof is formed with spring plate locating apertures 15 so positioned that when the spring plank is assembled with the side frame, said apertures are located on the longitudinal center line thereof.

Positioned on the spring plank 12 is a 70 spring plate 16 formed with locating bosses 17 which engage in the apertures 15 in the spring plank and properly position the spring plate 16 and the associated springs 18. In the embodiment illustrated, the bosses 17 are formed by pressing substantially conical extensions downwardly from the spring plate 16 but it is obvious that they may be of any desired construction. The spring retaining plate 16 is preferably of non-circular form as illustrated and in the embodiment disclosed is of substantially hexagonal shape corresponding with the grouping of the springs.

This form of plate is advantageous 90 because it compels the party assembling the same to properly position it with respect to the spring plank and thereby cause the associated springs to be properly positioned so that the desired distribution of the load is effected. Referring to Fig. 2, it will be seen that the center of the group of springs is at approximately the intersection between the longitudinal center line of the frame and the center line of the spring plank. The transversely extending sides of the hexagonal spring plate extend in substantially the same direction as the upturned flanges of the spring plank and the distance along a greater axis of the spring plate is greater than 95 the distance between the flanges of the spring plank, hence the group of springs and its associated spring plate must be inserted in the position shown. In accordance with my invention, I employ a six unit nest 100 of springs positioned directly on the spring plate 16 and properly located with respect thereto by means of upstanding annular flanges or collars 19 which engage the innermost springs 20 of the spring groups or 105 units 18.

In accordance with my invention, the 110 spring groups or units 18 are arranged in hexagonal form, that is, they preferably form in outline an equilateral or regular hexagon and, when normally positioned, a long axis of said hexagon is disposed transversely of the side frame or longitudinally of the spring plank. The four spring units 120 not lying on the transverse or long axis of the six unit nest of springs are preferably positioned in standard location, that is, they are formed and located to correspond with the position of the four outer springs of the A. R. A. standard five unit nest of springs 125 130

normally employed with seventy ton frames with standard clearance only therebetween. In this way, it is possible to make the associated spring plank 12 of standard width merely being of sufficient length to accommodate the outermost spring group or unit. Instead of the single boss normally employed on each end of the spring plank for limiting outward shifting of the nest of springs, I 10 preferably employ two bosses 21, disposed as indicated particularly in Figure 2, so as to cooperate with the three outermost spring units. The locating bosses 17 are so arranged with respect to the collars 19 that the springs 15 balance about said bosses, that is, said bosses preferably lie on the longitudinal center line of gravity of said springs so that, when engaged in the locating apertures 15 in the spring plank 12, the springs balance about 20 the longitudinal center line of the frame.

The upper spring plate 22 may be constructed identical with the lower spring plate 16 but is reversed in position so that the collars 19 extend downwardly and engage the inner springs 20 and the locating bosses 17 extend upwardly and engage in corresponding apertures, not shown, in the truck bolster 23. Referring particularly to Figure 3, it will be seen that because of the innermost spring 25 group or unit, it will be necessary to extend the substantially horizontal spring engaging web or face 24 of the bolster inward as shown at 25. That, however, is only done locally so as not to decrease the bolster strength any 30 more than is necessary, the outer sides of the sloping portion 26 of the lower web of the bolster starting to slope at its standard location, as indicated at 27, and the horizontally extended portion 25 of the web 24 being 35 thickened to avoid decreasing the bolster strength.

For retaining the spring plates 16 and 22 in the desired assembled relation with respect to the springs therebetween, and placing said springs under any desired initial compression or stress, the central portions of the spring plates are cupped or embossed toward each other as indicated at 28, said cupped portions being perforated at 29 for receiving 45 a retaining bolt or other means 30 extending therebetween. The portions 28 of the spring plates are formed sufficiently deep to enable a short enough bolt 30 to be employed so as not to necessitate perforating 50 the associated spring plank and side frame for receiving said bolt when the springs are compressed under load. In other words, the plates may be cupped sufficiently to allow 55 for using a retaining bolt, the length of 60 which is the same or less than the solid height of the springs. If desired, however, the customary retaining bolt apertures may be formed in the spring plank and side frames so that the nest of springs constructed in 65 accordance with my invention may be re-

placed by an A. R. A. standard five unit nest of springs.

For adequately reinforcing the spring plank seat or upper web 6 of the tension member 3 of the side frame with respect to the novel arrangement of springs in accordance with my invention, said web 6, which is increased to a maximum directly under the innermost and outermost spring units 18, is reinforced at these points directly under said springs, preferably by traversely disposed upright webs or brackets 31 extending downwardly between the extended flange portions 10 and 11 and the adjacent webs 8 and 9, respectively. As will be seen from a consideration of Figure 3 particularly, these webs are substantially triangular in the embodiment illustrated although the free edges thereof may be curved, as illustrated, so that said edges are substantially horizontal where the webs merge with the lower edges of the side webs 8 and 9. From a consideration of Figure 4, it will be seen that the main upright webs 8 and 9 of the tension member are almost ideally located for the support of the four intermediate spring units as the centers of said spring units lie almost directly over said webs while the transverse webs or brackets 31 are similarly located for supporting the innermost and outermost spring units. Although the aforescribed reinforcement is especially designed for the six unit group of springs in accordance with my invention, yet it is also adapted for supporting the A. R. A. standard five group nest of springs when the same is positioned so that its center of gravity lies on the longitudinal center line of the side frame.

From the foregoing disclosure, it will be seen that I have devised a construction which provides for a twenty per cent increase in spring capacity without radically changing the construction of the side frames, spring plank and associated bolster. With said modified members, the A. R. A. standard five group nest of springs may be employed interchangeably with the spring arrangement disclosed in accordance with my invention if the spring plank and side frames are provided with apertures underlying the spring plate retaining means for receiving said means upon compression of the springs. When using the standard five group nest of springs there will, of course, be slightly more clearance at the place of engagement of the bolster therewith and the bolster will overhang to a greater extent than with the present arrangement. In the same way, the spring plank, if used with the standard arrangement of springs, will be slightly longer than is absolutely necessary.

Having now described my invention, what I claim is:

1. In a car truck, in combination, a side frame formed with a bolster opening and a

- spring plank seat portion beneath said opening, a six unit nest of springs supported by said spring plank seat portion of the side frame, said springs being arranged in hexagonal form and positioned so as to balance about the longitudinal center line of the side frame, spring plates disposed one above and one below said nest of springs, and retaining means extending between said plates to hold the springs assembled independently of the other parts of the truck.
2. In a car truck, in combination, a side frame formed with a bolster opening and a spring plank seat portion beneath said opening, a spring plank positioned on said spring plank seat portion of the frame, a unitary spring plate supported on said spring plank, a six unit nest of springs supported on said spring plate above the spring plank seat portion of the frame, said spring plate being provided with means properly locating the springs with respect thereto and other means properly locating it with respect to the spring plank, said springs being arranged in hexagonal form with a long axis thereof disposed transversely of the frame and the springs so arranged that their center of gravity corresponds with the longitudinal center line of the frame.
3. In a car truck, in combination, a side frame formed with a compression member, a tension member and bolster column guides spacing intermediate portions of said compression and tension members and leaving a window opening therebetween, the portion of the tension member, beneath the window opening, being laterally widened to form a spring plank seat, a spring plank supported on said seat, a six unit nest of springs supported on said spring plank and arranged in hexagonal form with a long axis thereof disposed longitudinally of the spring plank whereby the springs may be used with a plank of standard end width, said springs being disposed on said spring plank so that the center of gravity of the group coincides with the longitudinal center line of the side frame, a bolster, the corresponding end of which is supported by the springs, and retaining means for said springs serving to place the same under initial compression and acting to properly space the springs with respect to each other, the spring plank and bolster.
4. In a car truck, in combination, a side frame formed with a bolster opening and a spring plank seat portion underlying said opening, a six unit nest of springs arranged with standard clearance only therebetween as a substitute for a standard five unit nest of springs and supported by means of the spring plank seat portion of the frame, said six unit nest of springs being arranged as an equilateral hexagon with four of the spring units thereof positioned to correspond with the four outer spring units of the standard five

unit nest of springs, the other two spring units being positioned, respectively, inwardly and outwardly of the position of the central spring unit of the standard five unit nest of springs, all of said springs corresponding in size with the spring units of a standard nest of springs.

5. In a car truck, in combination, a side frame formed with a bolster opening and a spring plank seat portion beneath said opening, a spring plank with its corresponding end supported on said spring plank seat portion and in turn supporting a unitary spring holding device, a six unit nest of springs arranged in hexagonal form with the long axis disposed transversely of the side frame and positioned on the device so that the center of gravity of the nest of springs lies on the longitudinal center line of the side frame, said springs being of a size corresponding with the springs of a standard five unit nest of springs whereby the spring plank may be made of standard end width but correspondingly lengthened on account of the increased width of the nest of springs.

6. In a car truck, in combination, a side frame formed with a bolster opening and a spring plank seat portion beneath the bolster opening, a spring plank positioned on said seat portion, a six unit nest of springs, hexagonally arranged with a long axis thereof disposed transversely of the frame, supported on said spring plank above the spring plank seat portion of the frame, a pair of spring plates positioned one above and one below said nest of springs, retaining means joining said spring plates to maintain the same properly assembled and under any desired initial stress, the ends of the spring plank being of standard width on account of the arrangement of the springs but correspondingly lengthened to correspond with the increased width of the nest of springs over the standard five unit nest of springs.

7. In a car truck, in combination, a side frame formed with a compression member, a tension member and bolster guide columns spacing intermediate portions of the compression and tension members, leaving a window opening therebetween, that portion of the tension member, beneath the window opening, being laterally widened to form a spring plank seat portion, a spring plank supported on said seat portion, a six unit nest of springs supported on said spring plank, said springs being arranged with their units disposed as an equilateral hexagon with a long axis extending transversely of the frame and the four spring units not lying on the long axis being positioned to correspond with the four outer spring units of a standard five unit nest of springs, whereby the spring plank may be made of standard width at its ends, a bolster, the corresponding end of which is supported by the springs, spring plates posi-

- tioned one above and one below said springs, cuffed toward each other at the center of the spring arrangement and retained by a bolt passing through the cuffed portions of said plates, said cuffed portions being sufficient in depth to permit compression of the springs without the necessity of providing an aperture in the spring plank to correspond with the retaining bolt, said spring plank outwardly of the springs being formed with retaining bosses for limiting spring shifting with respect to the plank.
8. In a car truck, in combination, a side frame formed with a bolster opening and a spring plank seat portion beneath said opening, a six unit hexagonally arranged nest of springs supported by said spring plank seat portion of the side frame, spring plates positioned one above and one below said springs and provided with locating bosses on the center line of the frame and adapted for engagement with corresponding apertures of standard location, said spring plates being also cuffed toward each other centrally of the spring arrangement, whereby they may be connected together by a retaining bolt shorter than normal, whereby sufficient room is allowed for compression of the springs without perforating the spring plank for the reception of said bolt.
9. In a car truck, in combination, a side frame formed with a bolster opening and a spring plank seat portion beneath said opening, a spring plank positioned on said seat portion of the frame, a hexagonally arranged six unit nest of springs supported on said spring plank above the spring plank seat portion of the frame, spring plates for said springs, said plates being provided with securing means extending between central portions thereof which are cuffed toward each other and substantially conical locating bosses on said plates arranged to engage in standard apertures on the center line of the frame.
10. In a car truck, in combination, a side frame formed with a compression member, a tension member, and bolster guide columns spacing intermediate portions of said compression and tension members and leaving a window opening therebetween, that portion of the tension member beneath the window opening, being widened to form a spring plank seat portion, a spring plank supported on said seat portion, a six unit nest of springs supported on said spring plank over the seat portion, said spring units being arranged as an equilateral hexagon with a long axis thereof arranged transversely of the side frame, a bolster, the corresponding end of which is supported by the springs, spring plates positioned, respectively, above and below said springs and provided with spring positioning flanges and central cuffed portions extending toward each other, said cuffed portions being apertured, and means extending
- through said apertures for holding said spring plates in position with respect to said springs, said spring plates being provided with substantially conical locating bosses arranged for engaging in normally located apertures in the bolster and spring plank, respectively, whereby the arrangement may be used interchangeably with the standard arrangement.
11. In a car truck, in combination, a side frame formed with a compression member, a tension member and bolster column guides spacing intermediate portions of said compression and tension members and leaving a bolster opening therebetween, that portion of the tension member, beneath the bolster opening, being generally box shape in cross section with an upper relatively wide imperforate web forming a spring plank seat portion, a lower web narrower than said upper web, webs extending between the outer edges of said lower web and the upper web, a spring plank supported on said upper web, a six unit nest of springs supported on said spring plank, said group of springs being arranged as an equilateral hexagon with its center of gravity lying on the longitudinal center line of the side frame and its long axis disposed transversely of the side frame, the supporting upper web of the side frame being reinforced for properly supporting said springs by web portions extending, respectively, outwardly and inwardly under said web between the same and the adjacent side webs and below the extreme inner and outer spring units of said six unit nest of springs.
12. In a car truck, in combination, a side frame formed with a compression member, a tension member and bolster column guides spacing intermediate portions of said compression and tension members and leaving a bolster opening therebetween, the portion of the tension member, beneath the bolster opening, being formed generally box shape in cross section with an upper relatively wide web serving as a spring plank seat portion tying together the tops of the tension member side walls and adapted for supporting a spring plank upon which rests a six unit nest of springs hexagonally arranged with its long axis disposed transversely of the side frame, the upper web of said box section being widened to a maximum beneath the center of the nest of springs and reinforced at this point by substantially triangular reinforcing webs extending beneath the spring plank seat portion to the side walls of the box section of said tension member.
13. In a car truck, in combination, a side frame formed with a compression member, a tension member and bolster column guides spacing intermediate portions of said compression and tension members and leaving a window opening therebetween, that portion of the tension member, beneath the window

opening, being widened to form a spring plank seat portion connecting the side walls of the member, a spring plank supported on said seat portion, a six unit nest of springs hexagonally arranged with its long axis transversely disposed with respect to the side frame supported on said spring plank with its center of gravity positioned on the longitudinal center line of the side frame, a bolster supported by said springs with a substantially horizontal surface formed directly above said springs and corresponding in area with the plan thereof, said horizontal surface being extended locally toward the center of the bolster to allow for the reception of the innermost spring unit.

14. In a car truck, in combination, a side frame formed with a compression member, a tension member and bolster guide columns spacing intermediate portions of said compression and tension members, leaving a window opening therebetween, that portion of the tension member, beneath the window opening, being laterally widened to form a spring plank seat portion, a spring plank supported on said seat portion, a six unit nest of springs supported on said spring plank, two of the units of said nest being disposed substantially on the axis of the spring plank, and the four spring units not lying on said axis being positioned to substantially correspond with the four outer spring units of a standard five unit nest of springs, whereby the spring plank may be made of substantially standard width at its ends, a bolster, the corresponding end of which is supported by the springs, and spring plates positioned one above and one below said springs, cupped toward each other and retained by a bolt passing through the cupped portions of said plates.

15. In a car truck, in combination, a side frame formed with a compression member, a tension member and bolster guide columns spacing intermediate portions of the compression and tension members, leaving a window opening therebetween, that portion of the tension member, beneath the window opening, being laterally widened to form a spring plank seat portion, a spring plank supported on said seat portion, a six unit nest of springs supported on said spring plank, said springs being arranged with their units disposed as an equilateral hexagon with a long axis extending transversely of the frame and the four spring units not lying on the long axis being positioned to correspond with the four outer spring units of a standard five unit nest of springs, whereby the spring plank may be made of standard width at its ends, a bolster, the corresponding end of which is supported by the springs, spring plates positioned one above and one below said springs, cupped toward each other at the center of the spring arrangement and re-

tained by a bolt passing through the cupped portions of said plates.

16. In a car truck, in combination, a side frame formed with a compression member, a tension member, and bolster guide columns 70 spacing intermediate portions of said compression and tension members and leaving a window opening therebetween, that portion of the tension member, beneath the window opening, being widened to form a spring plank seat portion, a spring plank supported on said seat portion, a six unit nest of springs supported on said spring plank over the seat portion, said spring units being arranged as an equilateral hexagon with a long axis there-of arranged transversely of the side frame, a bolster, the corresponding end of which is supported by the springs, spring plates positioned, respectively, above and below said springs and provided with spring positioning flanges and central cupped portions extending toward each other, said cupped portions being apertured, and means extending through said apertures for holding said spring plates in position with respect to said springs.

17. A side frame for railway car trucks comprising a compression member, a tension member and bolster guide columns spacing intermediate portions of said compression and tension members and leaving a window opening therebetween, that portion of the frame, beneath the window opening, being box shaped in cross section and formed with an upper relatively wide web connecting the sides of the portion and serving as a spring plank seat, said web being formed with standard spring plank squaring lugs on its upper surface and reinforced at its widest point by upright transversely disposed substantially triangular bracket portions extending from the spring plank seat portion to that portion of the tension member therebeneath.

18. A spring plate for a six unit spring group formed with a central cupped portion 110 perforated for the reception of retaining means for said group, annular spring centering flanges hexagonally disposed for the six spring units and spaced substantially conical locating bosses disposed on said plate 115 on a short center line thereof and adapted for engagement in apertures arranged for standard spring plates.

19. A railway car truck including a side frame, a truck bolster, a spring plank, a group of more than four springs symmetrically arranged about a common point with at least two of said springs in alignment with the longitudinal center line of said spring plank, said spring plank having upturned flanges 120 and a pair of spring retaining plates of non-circular form adapted to interfit with said flanges to compel the correct alignment of said springs when assembling.

20. A car truck including a side frame, a 130

bolster, a spring plank with upturned flanges, a group of at least six springs symmetrically arranged about a common center, a pair of connected hexagonal retainer plates carrying 5 spring centering projections adapted to position said group of springs between said flanges so that at least two springs are aligned with the longitudinal center of said spring plank.

10 21. In a railway truck, in combination, side frames having compression and tension members with bolster guide columns spacing intermediate portions thereof leaving window openings therebetween, those portions of the 15 tension members beneath the window openings forming plank seats, a spring plank supported on said seats, a six unit nest of springs supported on each end of said plank and arranged in regular hexagonal form and so 20 disposed that the plank may be of standard end with, a bolster, the ends of which are supported by said nests of springs, and retaining means for said springs serving to hold the nests assembled with the springs thereof 25 properly spaced with respect to one another.

22. A side frame for railway trucks comprising a compression member, a tension member, bolster guide columns spacing intermediate portions of said compression and 30 tension members leaving a window opening therebetween, that portion of the frame beneath the window opening being box shaped in cross section with an upper web thereof serving as a spring plank seat, said web being of greatest width midway between said 35 guide columns and reinforced at that location by brackets extending downwardly to the adjacent portion of the tension member therebeneath.

40 In testimony whereof I affix my signature.
